UNITED STATES PATENT OFFICE.

WILLIAM M. BRUCE, JR., OF SPRINGFIELD, OHIO, ASSIGNOR TO THE UNITED TELEGRAPH & CABLE COMPANY, OF SPRINGFIELD, OHIO, A CORPORATION OF OHIO.

TELEGRAPHY.

1,073,886.

Specification of Letters Patent. Patented Sept. 23, 1913.

Application filed August 24, 1912. Serial No. 716,870.

To all whom it may concern:

Be it known that I, WILLIAM M. BRUCE, Jr., a citizen of the United States, residing at Springfield, in the county of Clark and State of Ohio, have invented certain new and useful Improvements in Telegraphy, of which the following is a specification.

My invention relates to improvements in telegraphy and the object of the invention is 20 to provide a system of telegraphy in which telegraphing may be accomplished by the ordinary make and break circuits and through lines of high resistance and of large capacity without interference from either the 15 resistance, each current or capacity troubles.

Heretofore in the ordinary telegraphing system it has been difficult to work over long lines owing to the resistance and the current absorption in lines of large capacity and so 20 far as I know all telegraphing has been accomplished practically only by use of a direct current. I accomplish the object herein sought and make it possible to telegraph over lines and cables of any length and size by 25 using alternating current and providing means for absorbing the alternations without interfering with the make and break impulses used for operating the usual receiving instruments.

30 Briefly stated the invention consists essentially in employing in connection with a telegraph line an alternating or interrupted current with the usual transmitter and a delicately adjusted relay which will not only 35 respond to the alternations of current but also to the impulses caused by the make and break by the transmitter and this relay is adapted to repeat into a local circuit in which is located a second relay rendered slow or 40 sluggish in a suitable way by copper jacket or otherwise so that the rapid vibration caused by the current alternations would keep this slow relay energized but the impulses caused by the make and break of the 45 main line current would not be sufficiently rapid to retain this relay energized and hence the second or slow relay would respond to the make and break impulses but would not respond to the rapid alternations of the main 50 line and relay. This second and sluggish relay can be made to repeat into any desired local circuit containing any usual form of receiving instrument, either a sounder or re-

cording instrument or could be so constructed that it could operate itself as a receiving 55 instrument if desired.

In the accompanying drawing I have illustrated my improved system of telegraphy by means of a diagrammatic drawing, in which *a* represents a main telegraph line or cable of 60 any desired length, *b* is an alternating current generator of any usual form, one pole of which may be grounded at *G* and the other pole connected to line wire *c* and to any suitable make and break transmitter *d*, 65 such as the usual telegraph key or other form of transmitter, thence by wire *e* and condenser *f* and wire *g* to relay *h* and by line *a* to any desired distance and to any number of relays *h* and to any point desired. The 70 relay *h* is preferably a relay of high resistance and is provided with a delicate adjustment so as to respond to any vibrations or impulses which may pass through it. The armature spring 1 of the relay *h* when energized, engages contact 2 which is connected by wire 3 to a local battery *B* and line wire 4, relay 5, wire 6 to spring 1, thus making a local battery circuit including the relay 5. This relay 5 is of the sluggish type and does 75 not differ materially from the usual slow relays which are employed in automatic telephony for remaining energized and thus holding a circuit closed while impulses of current are passing through it, while other 80 or normal relays in the same circuit are responding to the impulses. It is adjusted so that while it will not respond to alternations of an ordinary alternating current which are repeated by the relay *h* but will be deenergized by current interruptions of any considerable length. This relay 5 is provided with the usual armature contacts 7 and 8 in a local circuit 9, 10, 11, 12, 13, 14 and 15 which includes any suitable form of receiving device 85 16. This may be the usual telegraph sounder or any form of recording device.

In operating this system any of the well known forms of telegraphing may be employed. The alternating current used is 100 preferably of low frequency, say, from 10 to 20 cycles. By manipulating the sending device *d*, which is an ordinary telegraph key, the slow relay will respond to the current interruptions and repeat these to the receiving device 16 in exactly the same way as if

a direct current was employed with the usual relay repeater. The relay *h* will respond not only to the alternate current vibrations, but also to the impulses from the 5 make and break sending device but the relay 5 will remain energized so long as the vibrations caused by the alternations of the current are passing through the relay *h*, but it will be deenergized when the current is broken 10 by the transmitting device, and in this way any ordinary or known system of make and break telegraphy can be employed over high resistance lines and by the aid of an alternating current.

15 By this system lines, such as ocean cables, which are now operated with considerable difficulty and require very delicate adjusted instruments and large conductors and then operated at a minimum speed, can be operated 20 at a maximum speed with small conductors and the usual instruments as neither the resistance or capacity influences will affect the alternating current and the alternations will be absorbed by the slow relay 25 so that the result will be the same as though a direct current were employed.

The condenser *f* is preferably used at the terminals or stations to prevent the electrostatic disturbances of earth current.

30 I have used this system through 240,000 ohms of resistance with the ordinary alternating current such as furnished from harmonic ringing devices of twenty cycles, while the maximum as used in telegraph, 35 in the use of direct current, is approximately 5000 ohms. The relays which were employed in this were for the line relays approximately 2000 ohms and for the local or slow relay approximately one ohm and furnished with the usual copper jackets of relays of this type.

An interrupted current having interruptions of substantially the same frequency as the frequency of an alternating current as 45 the frequency of an alternating current may be used instead of an alternating current under some circumstances and with fairly good results, and where an alternating current is described it is intended to cover either alternating or interrupted current.

50 Having thus described my invention, I claim:

1. A system of telegraphy comprising a main line, a source of alternating current, transmitters in said line, and line relays in 55 series with said transmitters adapted to respond to the alternations and to the interruptions of the transmitter, and a secondary circuit controlled by said line relay including an electro-magnet or relay slower to operate than the line relay and arranged to remain energized by the current alternations

and to operate in unison with the relays sent by the transmitters, as set forth.

2. In a system of telegraphy, a main line, a source of alternating current supply, a 60 relay in said line, a second relay slower to operate than said first relay and controlled by said first relay, and a make and break device in said line whereby said slow relay will respond to the current interruptions by 70 the make and break device but will not respond to the current vibrations of the current alternations, as set forth.

3. In a system of telegraphy, a main line, a source of alternating current, a current 75 interrupter, a condenser and a relay in series in said line, said relay being adapted to respond to the current interrupter, and to the current alternations, a second relay adapted 80 to remain energized by the current alternations in circuit with the repeating armature of said first relay and respond to the current interruptions and a source of current supply for said second relay and a receiving instrument in a local circuit controlled by the 85 armature of said second relay.

4. In a system of telegraphy, a line relay, and a second or sluggish relay controlled thereby, said line relay being adapted to respond to rapid vibrations of current and 90 retain said sluggish relay energized and said sluggish relay being adapted to be deenergized by a less rapid vibration or impulse transmitter over said line and through the line relay to said slow relay.

5. In a system of telegraphy, a main line, a source of alternating current to said line, means in said line for responding to the vibrations of said current and transmitting them into a local circuit and a slow relay in 100 said local circuit adapted to absorb the said vibrations but respond to interruptions of less frequency.

6. In a system of telegraphy, a main line, a source of alternating current to said line, 105 means in said line for responding to vibrations of said current and transmitting them into a local circuit, and a slow relay in said local circuit adapted to absorb the said vibrations, but respond to interruptions of 110 less frequency, and a second local circuit including a sounder controlled by said slow relay so that the interruptions of less frequency will be repeated to said sounder by said slow relay.

In testimony whereof, I have hereunto set my hand this 17th day of August 1912.

WILLIAM M. BRUCE, JR.
